UNITED STATES PATENT OFFICE.

CHARLES EDWARD WEST, OF HIGHAM HILL, WALTHAMSTOW, ENGLAND.

MACHINE FOR CASTING METALS.

1,376,661.

Specification of Letters Patent.

Patented May 3, 1921.

Application filed February 28, 1918. Serial No. 219,720.

To all whom it may concern:

Be it known that I, CHARLES EDWARD WEST, a citizen of the United Kingdom of Great Britain and Ireland, and resident of 5 11 Norfolk road, Higham Hill, Walthamstow, in the county of Essex, England, have invented certain new and useful Improvements in Machines for Casting Metals, of which the following is a specification such 10 as will enable others skilled in the art to which it appertains to make and use the same.

This invention relates to die casting machines of the kind in which coacting dies 15 or molds are capable of movement to and from a container positioned beneath them, and from which molten metal can be forced into the dies which are positioned one above the other and in which the molten metal is 20 forced upwardly by a plunger, through an opening in the lower die.

The invention consists in a construction in which coacting top and bottom dies are 25 slidably mounted in a frame, so that they can be raised vertically therein in two stages; that is to say, the dies are first raised together, and then the top die further raised independently so as to separate it from the bottom die; while the plunger for forcing 30 the molten metal into the dies is arranged so that it has an axial as well as a sliding movement in its cylinder.

After the dies are filled they are raised together by means of a balance lever or 35 levers or the equivalent, and are then separated by means of a screw shaft which lifts the top from the bottom die. The lower end of such screw shaft carries a boss or collar and also the sprue cutter which extends 40 through the top die.

When the dies are raised together, both slide over the sprue cutter, which remains stationary, and thus ejects the sprue or frozen metal from the bottom die, the screw 45 shaft being then operated to separate the top from the bottom die.

The boss or collar on the screw shaft is arranged in conjunction with an adjustable stop on the top die to allow of lost 50 motion between such parts, and permit the use of dies of different depths. Such stop is adjusted so that the sprue cutter is withdrawn from the bottom die before the top die is separated, the latter operation being 55 effected by the engagement of the boss or collar on the screw shaft with said adjust-

able die stop, and as the top die is so lifted the molded articles are pushed out therefrom by means of screws mounted on the machine frame.

An example of my invention is shown in the accompanying drawings in which:—

Figure 1 is a front elevation of the machine,

Fig. 2 is a side elevation of the machine, 65

Fig. 3 is a cross section at about the line 3—3 of Fig. 1,

Fig. 4 shows in plan a general arrangement of the base of the machine and,

Fig. 5 is a detail view partly in section and 70 drawn to a larger scale, illustrating the adjustable means employed for connecting the top die and screw shaft.

The machine illustrated comprises a table or base *a* supporting a gallows or frame *b* and having in it a metal container *c* heated by the gas and air burners *d*. The table also supports the bottom die *e* on which the top die *f* rests. The metal container *c* in the base is furnished with a cylinder *c'* 75 to receive a plunger *g* operated by a lever *h* the stroke of which is controlled by the bar *i*. The plunger has a spiral groove *g'* which, coacting with pins in the cylinder *c'*, imparts a rotary movement to the plunger as it moves to and fro therein. The molten metal is drawn into the cylinder *c'* from the metal container *c*, through the opening *j* upon the outstroke of the plunger and upon its instroke is forced out of the cylinder through the passage *k*, and the opening *l* in the bottom of the lower die *e*.

The bottom die *e* is carried on a bottom die plate *1*, and the top die *f* on a top die plate *2*, both die plates being furnished with lateral horn plates *4* which engage with and slide over the side members of the frame *b*, when the dies are raised and lowered, while the bottom die *e* is preferably water cooled by means of the pipe *z* which is furnished 100 with suitable flexible connections not shown.

A lever *m* is employed to lift the dies simultaneously and is connected to the bottom die for that purpose, the amount of the lift being controlled by the adjustable screws 105 *m'*. The top die *f* is separated from the bottom die by means of a screw shaft *r* which is mounted in the frame *b*, and carries a fly-wheel *s* at its upper end, while to facilitate lifting the dies the lever *m* is counter weighted and balance weights *t* are connected to the upper die *f*.

The top die plate 2 carries a bridge piece *p* which affords a free passage for the screw shaft *r*, but forms an abutment for a boss or collar *q'* arranged on the lower end of such shaft together with the sprue cutter *q*, which latter extends through the upper die as shown. The free passage of the screw shaft through the bridge piece allows the top die *f* to be raised together with the bottom die by means of the lever *m*, while the screw shaft *r* and sprue cutter *q* remain stationary. Thus as the dies are lifted by the lever *m*, the lower end of the sprue cutter ejects the sprue from the bottom die, and while the dies are so raised the screw shaft *r* is operated to withdraw the sprue cutter from the bottom die, and lift the top die therefrom. During the withdrawal of the sprue cutter the shaft *r* moves up independently of the top die, but as soon as the withdrawal is completed, the boss *q'* bears against the bridge piece *p* so that the top die is lifted by the further ascent of the screw shaft.

25 A sleeve piece *r'* is screwed into the head of the bridge piece *p*, see Fig. 5, and serves to regulate the upward travel of the sprue cutter *q*, so that the length of its travel can be adjusted according to the depth of the dies employed, and thus permit of the use of dies of different depths.

30 Adjustable screws *m*² fixed to the frame, pass through openings in the top die plate and by contact with the plate *f'* in the top die push out the casting as the top die is lifted, while a hand wheel or nut *u* on the screw shaft *r* serves to lock the dies together when lowered into position for casting.

Assuming the machine to be at work and 40 properly adjusted as to delivery of metal, lift of dies, etc., for the article required, the procedure is substantially as follows. The dies are brought to their lowermost position and locked together by the hand wheel or 45 nut *u*, the plunger *g* is withdrawn by lever *h* and the molten metal passes into the cylinder *c'* through the aperture *j*. The plunger is then thrust inwardly and forces the metal out of the cylinder through the 50 passage *k* and opening *l* into the dies. The dies are unlocked by releasing the hand wheel or nut *u* and then lifted by lever *m* while the screw shaft *r* remains stationary, so that the sprue is removed by the lower 55 end of the sprue cutter *q* as the dies ascend. The fly wheel *s* is then turned to raise the screw shaft *r* which first withdraws the sprue cutter from the lower die, and then brings the boss or collar *q'* against the lower 60 end of the adjustable sleeve *r'* in the bridge *p*, thus lifting the top die which holds the casting. As the top die ascends with the screw shaft and sprue cutter, the plate *f'* therein, comes in contact with the stops *m*², 65 and so pushes out the casting. After the

casting is removed the fly wheel *s* is turned to again lower the top die, the dies being then brought down to their lowermost position and the process repeated.

What I claim and desire to secure by Letters Patent is:—

1. A machine for casting metal comprising a pair of superposed dies each slidably mounted in a frame, means for lifting said dies together therein, screwing means for further lifting the top die in said frame and a sprue cutter carried on said screwing means and extending through said dies so as to remove the sprue as the same are lifted together, said frame also supporting a bath in which metal is heated and from which it is injected into the dies by means of a plunger fitted in a cylinder so as to rotate axially as it slides to and fro therein, and apertures connecting said cylinder to the metal bath and the dies respectively.

2. In a machine for casting metal articles the combination of a pair of superposed dies each slidably mounted in a frame, means for lifting said dies together, screwing means for further lifting the top die in said frame to separate the raised dies, a sprue cutter carried by said screwing means and extending through the dies so as to remain stationary as the same are lifted, and adjustable means for regulating the withdrawal of the sprue cutter from the raised bottom die, according to the depth of the dies used.

3. In a machine for casting metal articles the combination with a vertical frame of a pair of superposed co-acting dies each slidably mounted therein, means for raising said dies simultaneously in said frame, a screw shaft and adjustable means connecting same to the top die whereby the latter is further raised in said vertical frame to separate the raised dies, means for ejecting the casting from the top die as the latter is separated from the bottom die, a sprue cutter carried by said screw shaft and extending through the dies so as to remain stationary and eject the sprue as the dies are simultaneously lifted, said screw shaft withdrawing said sprue cutter when operated to separate the top die, and means on said screw shaft for locking and unlocking said superposed slid- 110 able dies when same are lowered in said vertical frame.

4. In a machine for casting metal articles the combination with a vertical frame of a pair of superposed co-acting dies each slidably mounted therein, means in connection with the lower die for raising said dies simultaneously in said frame, a screw shaft connected to the top die by a bridge-piece carrying an adjustable sleeve which co-acts with a boss on said shaft to allow lost motion between the latter and said top die; the raised top and bottom dies being separated by further lifting said top die through said 130

screw shaft, means on said vertical frame for ejecting the casting from the top die as the latter is separated, a sprue cutter carried by said screw shaft and arranged to remain 5 stationary and extend through the dies and eject the sprue as said dies are simultaneously raised, said sprue cutter being withdrawn as the screw shaft is operated to separate the top die, and a nut on said screw 10 shaft for locking and unlocking said superposed sliding dies when the same are lowered in said vertical frame.

5. A die casting machine comprising a vertical frame, a pair of superposed co-acting 15 dies each slidably mounted in said frame, an inclosed container for molten metal positioned below said dies and adapted to form a rest therefor when same are lowered for casting, means for heating said container 20 from which latter the molten metal is injected into said dies by a plunger fitted in a cylinder so as to rotate axially as it slides to and fro therein, apertures and passages connecting said cylinder to said container 25 and dies respectively; means connected to

the lower die for raising said dies simultaneously in said vertical frame, a screw shaft adjustably connected to the top die, for further lifting the latter, so as to separate the raised dies in said vertical frame, means 30 for ejecting the casting from the top die as the latter is separated from the bottom die, a sprue cutter carried by said screw shaft so as to remain stationary and extend through the dies and eject the sprue as said 35 dies are simultaneously raised, said sprue cutter being withdrawn by said screw shaft when same is operating to separate the top die, said die raising and separating means also serving to return said dies separately to 40 the casting position, and a nut on said screw shaft for locking and unlocking said dies, substantially as described.

In witness whereof I have hereunto set my hand in presence of two witnesses.

CHARLES EDWARD WEST.
